ATTORNEY

UNITED STATES PATENT OFFICE.

THOMAS J. SANDS, OF UTICA, NEW YORK.

SLUG OR BUNCH CATCHER FOR YARN.

No. 850,400.

Specification of Letters Patent.

Patented April 16, 1907.

Application filed May 23, 1903. Renewed August 11, 1906. Serial No. 330,143.

To all whom it may concern:

Be it known that I, THOMAS J. SANDS, of Utica, in the county of Oneida and State of New York, have invented certain new and useful Improvements in Slug or Bunch Catchers for Yarn; and I do hereby declare that the following is a full, clear, and exact description thereof, which will enable others skilled in the art to which it appertains to make and use the same, reference being had to the accompanying drawings, and to the letters of reference marked thereon, which form part of this specification.

The object of my invention is to provide an improved slug or bunch catcher for yarn wherein provision is made for readily and conveniently threading the device and for removing the bunches and slugs and wherein provision is made for adjustments for different sizes of yarn in an efficient and convenient way.

In the drawings, Figure 1 shows a perspective view of my device in operation. Fig. 2 shows the same in the position which the parts assume when a bunch or slug has been caught. Fig. 3 is a side elevation of the device. Fig. 4 shows the opposite side elevation from that shown in Fig. 3. Fig. 5 shows one edge view, and Fig. 6 the other edge view, of the device.

Referring to the reference letters and figures in a more particular description, 1 indicates the frame or body of the device, which is preferably formed of sheet material and at the lower end with a slotted arm or part 1^a, by means of which the device may be secured in position for use. The arm shown in the drawings extends in a vertical direction, although it may be made to extend in a horizontal direction or in any other way to suitably mount the device for use. The body or frame part is provided at one side with an angular wall portion 1^b, which supports the yarn-guide eye 2, and the same is provided with a V-shaped opening 3, permitting the ready introduction of the yarn into the device.

The bunch-catcher 4 is pivoted at 5 and eccentric to the pivot is provided with a toothed face 4^a, over or immediately above which the yarn is drawn. Over the rear portion of the toothed face is located when in normal working position an opposing member which, as shown, consists of a roller 6,

mounted on a pivot to rotate freely. The pivot of the roller 6 is secured in the swinging end of the hanger 7. The hanger 7 is pivoted to the frame at 8 and is provided with side walls 9, which are preferably rounded at their upper end and project at their lower ends to a point substantially in line with the end of the roller 6. On the frame there is provided a stop 10, which limits the movement of the hanger 7 in one direction. There may also be provided the stop 11, which limits the movement of the hanger in the opposite direction. The pivot 5 of the catcher 4 is supported in a vertically-movable carriage 12, which carriage is adjusted by means of a screw 13, supported in ears on the frame 70 against longitudinal movement and engaging with ears on the carriage. By means of the screw 13 the catcher 4 can be carefully and nicely adjusted in its position with reference to the face of the roller 6. Its position can also be adjusted by screw 5^a in the frame.

In threading the device the yarn can be dropped into the guide-eye through the opening 3 and passed around under the roller 6, 80 being guided by the walls 9. The yarn is drawn through the device in the direction from right to left, as shown in the drawings. When a slug or bunch presents itself, it will catch on the teeth of the catcher 4 and move 85 the toothed surface of the catcher in the direction of the movement of the yarn. In so doing the toothed face comes against the roller 6, and the bunch is firmly caught and held and the yarn will break. The attendant removes the bunch and ties the yarn and rethreads the device, when its operation will be immediately resumed. By adjusting the catcher 4 the relative position of the eye and the opposing surface or roller in connection 95 with which the yarn runs is not changed or altered. In removing the bunch or slug that has been caught from the device the attendant can readily swing the roller 6 on the hanger 7 out of the way and into the position 100 shown in dotted lines in Fig. 4. When not held in this position, it will by its own gravity assume its normal working position.

In Fig. 4 the catcher is shown adjusted to a position considerably below what might be 105 called its normal working position, although under certain circumstances if it was only desired to catch the larger and more objec-

tionable bunches the device might be used in the position shown in Fig. 4.

What I claim as new, and desire to secure by Letters Patent, is—

- 5 1. In a device of the character described, the combination of a pivoted catcher having a toothed face eccentric to the pivot, an opposite rotating member mounted to be temporarily displaced and automatically returned to its operative position, and a yarn-guide eye arranged in advance of the opening between the face of the catcher and the opposite member, substantially as set forth.
- 10 2. In a device of the character described, the combination of a pivoted catcher having a toothed face eccentric to the pivot, an opposing roller, a swinging hanger in which the roller is mounted to be temporarily displaced and automatically returned to its operative
- 15 20 position, and a yarn-guide eye arranged in advance of the opening between the face of

the catcher and the roller, substantially as set forth.

3. The combination in a bunch-catching device for yarn, of a main body or frame 25 supporting a fixed yarn-guide eye, a pivoted bunch-catcher having a toothed face and means for adjusting the same toward and from the yarn passing through the device, and a member opposite the face of the bunch-catcher, a hanger in which the opposing member is mounted adapted to be moved temporarily out of operative position, substantially as set forth.

In witness whereof I have affixed my signature, in presence of two witnesses, this 14th day of May, 1903.

T. J. SANDS.
